UNITED STATES PATENT OFFICE.

CHARLES SNELL, OF HOUSTON, TEXAS.

CENTER-GAGE AND MICROMETER.

1,365,289.

Specification of Letters Patent. Patented Jan. 11, 1921.

Application filed November 4, 1919. Serial No. 335,654.

To all whom it may concern:

Be it known that I, CHARLES SNELL, a citizen of the United States, residing at Houston, in the county of Harris and State 5 of Texas, have invented certain new and useful Improvements in Center-Gages and Micrometers, of which the following is a specification.

This invention relates to new and useful 10 Improvements in a center gage and inside micrometer.

One object of the invention is to provide an implement of the character described, which has been specially designed for the 15 purpose of providing a central support for dividers when the same are used in scribing castings and the like having a central bore. In finishing casting such as cylinder heads and the like having a bore, it is 20 often necessary to locate bolt holes around the flange of the casting and in order to describe the circle on which said holes are located, dividers are used, and when so used there must be a central support located at 25 the center of the bore. The device herein described has been designed for the purpose of providing said support.

Another object of the invention is to provide an inside micrometer for the purpose 30 of accurately measuring the inside diameter of the bore and for other similar purposes.

With the above and other objects in view, the invention has particular relation to certain novel features of construction, use, and 35 arrangement of parts, an example of which is given in this specification and illustrated in the accompanying drawings wherein:—

Figure 1, is a side elevation of the device, Fig. 2, is an end view thereof,

Fig. 3, is a transverse sectional view taken 40 on the line 3—3, of Fig. 2,

Fig. 4, is a side elevation of the drive screw,

Fig. 5, is an end view thereof,

Fig. 6, is a side elevation of the adjusting sleeve,

Fig. 7, is a side elevation of the adjusting sleeve extension,

Fig. 8, is an end view thereof,

Fig. 9, is a side view of a form of extension employed when the device is used as an inside micrometer,

Fig. 10, is an end view thereof and,

Fig. 11, shows the complete device as applied to the work.

Referring now more particularly to the

drawings wherein like numerals of reference designate similar parts, in each of the figures, the numeral 1 refers to the tubular casing which has a bore extending from end to end, one end of said bore, being reduced, forming the annular shoulder 2'. The numeral 2 refers to the drive screw whose ends are reversely threaded and said drive screw has the centrally located annular disk 3, 65 formed integrally therewith. This drive screw is located within the bore of the casing, one side of the disk 3, fitting against the shoulder 2', and the other side of said disk having the rib 4, formed integrally therewith. Screwed on to the respective ends of the drive screw are the respective adjusting sleeves 5 and 6, said sleeves fitting within the bore of the casing and the latter having the sleeve like bushing 7, fitted therearound. 75

The inner end of said bushing fits against the disk 3, and has opposing notches 8, 8, which receive the rib 4, and clutch said bushing with the drive screw. The bushing 7 is retained in place by means of the cap 9, 80 which is threaded on to the corresponding end of the casing 1. The adjusting sleeves 5 and 6, have the respective key ways 10, 11 and set screws 12 and 13 are threaded through the casing, 1, and cap 9, respectively, and their inner ends project into said key ways to hold the adjusting sleeves against turning, but they permit the lengthwise movement of said sleeve on the drive screw. The top side of the casing, 1, is flattened as at 14 and has the centrally located recess 15, which forms a central support for the dividers when the same are used in scribing a circle around the bore 16 of the casting 17. 95

In use, the device is placed in position within the bore and the bushing 7 is then turned thus projecting the adjusting sleeves 5 and 6, cut at each end until their outer ends engage against the walls of the bore to support the implement in position while in use. Thumb spaces 18, 18, are cut through the casing providing access to the bushing to turn the same and the exposed portion 19 of said bushing is knurled so that it may be 105 more easily turned.

When used in large bores, extensions 20 are attached to the respective ends of the sleeves 5 and 6. The extension 20 is provided at one end with a reduced stem 21 and a 110 transverse rib 22, said stem fitting within the outer end of the sleeve to which it is at-

tached and the rib 22 locking in the transverse groove 23 in the outer end of said sleeve.

- The device may be also used as an inside 5 micrometer for ascertaining the diameter of the bore and for ascertaining the relative diameters of different bores. When used as a micrometer in large bores, the extensions 10' are attached to the outer ends of the sleeves 5 and 6 the reduced stem 21' fitting into the outer end of the sleeve to which it is attached and the transverse rib 22', locking in the corresponding transverse groove 23.
- 15 For use as a micrometer the exposed section of the bushing 7 has a circumferential gage 24 to measure the amount of the rotation of said bushing and the outer end of one of the adjusting sleeves is suitably graduated as at 25 so that the distance it is projecting out from the casing may be accurately determined and the relative diameters of different bores, thus accurately ascertained.

25 What I claim is:

1. A device of the character described including a tubular casing, an externally threaded drive screw located therein having a disk near the center thereof, a rib on one side of said disk, adjustable internally threaded sleeves within said casing and

threaded onto the respective ends of said screw, a knurled bushing fitted within said casing and surrounding one of said sleeves, said bushing being connected to said screw 35 through said rib, so as to rotate the same as the bushing is rotated, said casing having thumb spaces cut therethrough to permit access to the bushing for rotating the same.

2. A device of the character described, including a tubular casing, a rotatable drive screw therein formed with an annular disk, a rib on one side of said disk, sleeves within the casing and threaded on to the respective ends of said screw, a bushing having end 45 notches into which the rib fits, said bushing surrounding one of said sleeves and operatively connected to the drive screw whereby the latter may be rotated, said casing having thumb spaces permitting access to said bushing whereby the same may be rotated, a circumferential gage formed on the bushing and a lengthwise gage formed on one of said sleeves.

In testimony whereof I have signed my 55 name to this specification in the presence of two subscribing witnesses.

CHARLES SNELL.
